UNITED STATES PATENT OFFICE.

ELWIN H. ROONEY, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

COILER-FRONT FOR CARDS.

1,175,561.

Specification of Letters Patent. Patented Mar. 14, 1916.

Application filed January 9, 1913. Serial No. 740,971.

To all whom it may concern:

Be it known that I, ELWIN H. ROONEY, a citizen of the United States, residing at Whitinsville, in the State of Massachusetts, have invented certain new and useful Improvements in Coiler-Fronts for Cards, of which the following is a specification.

The invention is an improved carding apparatus adapted to produce multiple slivers 10 condensed to such extent and with such degree of fineness and uniformity of weight as to be ready for immediate introduction to the slubber without the usual intermediate steps of drawing and doubling and without 15 the employment of a rubbing condenser.

The objects and particular features of the improvement reside in the provisions hereinafter set forth and claimed, whereby uniform slivers of sufficient fineness to be immediately converted into fine hank roving, 20 can be obtained from the fleece from a single card, which latter may run at its maximum efficiency, as may be required for the particular work in hand. Heretofore the card slivers have been passed directly to the 25 roving frame only when a rubbing condenser such as the Josephy condenser has been used or where a very coarse yarn for special purposes not requiring particular uniformity in 30 weight has been required.

To the end of obtaining the results of the Josephy condenser, as respects fineness of yarn, but without the complication and expense of such mechanism, the present invention 35 comprises a special coiler front in combination with a carding machine having its doffer cylinder suitably divided so as to deliver a plurality of separate webs or narrow fleece sections instead of a single or 40 double fleece as heretofore. In its most highly developed form the invention prefers eight or more of such fleece sections from the card and the present exemplification of the invention refers to eight of such sections. 45 The fleece sections from the card thus divided are simultaneously and independently condensed in two stages under conditions which are the same for each section and are then simultaneously and independently transferred also under equal condi-

tions to a corresponding series of sliver cans forming part of the front and into which each condensed section of sliver is discharged and coiled. By such method of handling each of the tenuous fleece sections 55 or slivers is preserved uniform in weight, although they have to travel different distances to their respective cans, and it thus becomes practicable to place such cans directly behind the slubber without resort to 60 doubling in the draw-frame.

The improvement is also concerned with the manner of construction and assemblage and the mode of operation of the several parts shown in the drawing, independently 65 of the number of subdivisions of the fleece, whereby the slivers are first partially condensed and then further and more compactly condensed, as they are laid in the cans, and whereby the apparatus is rendered 70 compact as to its arrangement of cans, and generally convenient of use for the purposes above stated.

The invention also includes certain features of economy of manufacture as well as 75 the adaptability of the front to existing cards, all as will be apparent to those skilled in this art and as will be pointed out in the claims.

In the drawings, Figure 1 is a top plan 80 view with parts broken out, of a doffer cylinder, of a divided card and a coiler front therefor employing this invention. Fig. 2 is a similar side elevation of the same. Fig. 3 is a top plan of the rotary can-stands of 85 the coiling mechanism; and Fig. 4 is a longitudinal section of the same apparatus as shown in Fig. 1, with a modified form of sliver table.

For convenience of illustration, all of the 90 familiar mechanism of the card proper has been omitted from these figures, excepting the parts more or less directly connected with the present invention. These include a portion of one end of the card frame 95 marked 1, the doffer cylinder 2 which is divided into eight sections, as above stated, by means of the seven tapes applied to the card clothing of the cylinder. The doffer driving gear is marked 3 and the usual doffer comb 100

is marked 4, being operated through the pulley 5 by the usual mechanism. The doffer comb is placed so as to co-act with the doffer cylinder at a point which is substantially tangent to the horizontal diameter of the cylinder. In such position the dirt liberated by the comb falls clear of the cylinder and not back upon it, as would be the case if located above the position indicated, and inasmuch as the present apparatus is specially useful for working waste cotton, which is usually more or less dirty, such location of the doffer comb is desirable.

The driven doffer gear 3 drives an adjustable train of gears 6 and 7, journaled on a gear plate 8 bolted to the side frame of the card, and from this train the delivery roll shaft 9 is driven through the gear 10, and from the same train a counter-shaft 11 is driven through an idler 12 and a shaft gear 13. The roll shaft 9 extends transversely across the card frame, being journaled on the projecting ends of the latter, and carries the lowermost rolls 14 of four pairs of calender rolls which are thus disposed parallel to the doffer comb and directly in front of it. The upper rolls 15 of these delivery rolls are of solid metal and rest by gravity upon their respective lower rolls 14, being held rotatably and removably in such position by the confinement of their end gudgeons in the supports 16, as shown in the drawings. The series of delivery rolls is separated from the doffer comb by a plate 35 or bar 17, which is secured to or against the rear sides of the supports 16, and supports a series of trumpets 18, of which there are two for each pair of rolls and one for each section of the divided fleece. The said sections immediately on leaving the doffer comb, move horizontally to their respective trumpets from which they are drawn by the delivery rolls, being thereby subjected to the first condensation. The delivery rolls 40 are provided with clearers 19, of a generally triangular shape, as indicated in Fig. 4, so that they will fit in the crotch between the rolls and the forward side of the trumpet plate 17. Such clearers are desirably made 45 of metal and solid so as to add weight to the upper delivery rolls 15 and thereby assist in the drawing of the fleece through the trumpets. Since the upper rolls rest upon the two fleece sections or slivers at 50 substantially equal distances from their ends, the pressure imposed on each of the two slivers is substantially equal and as each pair of rolls has the same size and weight and is equipped with the same 55 weight of clearer, the slivers emerging from the rolls are thereby equally condensed. The tapes on the doffer cylinder are likewise so arranged as to give an equal weight 60 per linear unit to each fleece section, so that 65 the slivers that move from the card to the

sliver table of the front are thus substantially identical in their physical condition.

From the delivery side of the calender rolls the slivers pass upwardly and without support to the lower edge of an apron 20, 70 which is part of the sliver table 21. This table is supported on end standards or legs 22 and overlies the set of sliver cans 23. The apron 20 is rearwardly and downwardly inclined, toward the doffer comb and the 75 condensing mechanism, so that each sliver is thus unsupported for an equal distance. The slivers are moved along the smooth surface of the apron and the flat surface of the table by means of a second series of pairs 80 of calender rolls by which they are further condensed and delivered into the cans. There is one pair of such rolls assigned to each sliver arranged above and eccentrically to the axis of rotation of the can beneath it 85 to which it delivers. In the preferred form of the invention, the eight or more sliver cans are arranged in two transverse rows of four cans each and the table is apertured above each can to let the sliver through as well as to accommodate and expose the calender rolls. The rolls for the sliver cans of the first row are arranged in alignment with each other and placed in such manner—each being eccentric to its can 90 as just stated—as to provide a passage between them through which the slivers for the second row of rolls may pass. The lower rolls of the first row are carried on a roll shaft 25 journaled in suitable brackets under the table and the upper rolls 26 rest by gravity thereon with their end gudgeons confined removably, in brackets 27. Each upper roll is provided with a clearer 28, which rests upon it. This clearer may be 95 swung back on its hinges when desired and the upper roll may be removed from its working position in the obvious manner.

The roll shaft 25 is connected by a beveled shaft gearing disposed beneath the table (see dotted lines in Figs. 1 and 2) with an other lower roll shaft such as 29, of which there may be as many as there are rows of cans. In the case of a twelve-sliver machine there will be two additional roll-shafts like 29, under the sliver table, each operating a transverse row of four cans, and all driven from the first roll-shaft 25. The shafts of the second, or second and third rows, may be and preferably are identical with the 110 shaft 25, except for the location of the lower rolls 30 thereon, which are arranged to provide a substantially straight course for each sliver. Each lower roll supports an upper roll 31, equipped with a holding bracket 27 115 and a clearer 28.

The set of roll-shafts 25 and 29 in the present case are driven positively and in unison with the card, for which purpose they are geared by means of an inclined 120 125 130

bevel gear shaft 32, with the transverse countershaft 11 above referred to. The shaft 32 is journaled at one end on the sliver table and at its lower end in a bracket 33 on 5 the card, at which point it carries a pinion engaged by a drive pinion on the counter-shaft 11. The countershaft also drives, through appropriate bevel gears, the upright shaft 34, which actuates the coiler mechanism. The latter is placed between the end standards or legs of the table and comprises a plurality of rotary plates or stands 35, upon which the sliver cans are adapted to be placed and by which they are 10 rotated when receiving the sliver. The stands 35 are mounted in a suitable casing and inter-connected by the gearing, as indicated by the dotted pitch circles, and driven from a spur gear at the foot of the shaft 20 34. All the cans are driven in the same direction.

In the form of the invention shown in Fig. 4, the construction and operation throughout is the same as in the form first 25 described and the calendar rolls 36 are disposed in the same relation on the sliver table as the rolls 24 and 26, but they are horizontal instead of one above the other and both are driven positively from the 30 shaft 32. Any suitable form of gearing for this purpose, not necessary to be shown, may be used. Each pair of calender rolls is placed directly beneath an aperture in the sliver table, or partly within such aperture, 35 and is eccentric to the axis of the can beneath it. The aperture in the table is provided with a hinged cover plate 37, which supports a trumpet 38, and may, if desired, form part of a usual stop motion mechanism. The trumpets 38 point downwardly 40 and directly into the bite of the rolls and their orifices are smaller than the orifice of the trumpet 18 on the card, so that each fleece section is condensed first only to such 45 extent as may be necessary to enable it to be lifted to the height of the sliver table and then is further and finally condensed just as it enters the can. It will be understood that the can stands for this form may 50 be the same as shown in Fig. 3.

Claims:

1. In apparatus of the kind described, a divided card having a sliver can for each section of the divided fleece, a sliver table 55 covering the cans and provided with a sliver apron extending downwardly toward the doffer comb of the card, in combination with means for delivering the fleece-sections from such comb to said apron and for conducting 60 the same along the latter and thence downwardly into their respective sliver cans.

2. In apparatus of the kind described, a divided card having a sliver table placed in front of it provided with a sliver-conducting 65 part extended downwardly therefrom to-

ward the doffer-comb of the card and spaced a substantially uniform distance from such comb, in combination with means on the table for condensing and moving the fleece sections, and a corresponding number of 70 sliver-cans receiving such sections and in which they are coiled.

3. Apparatus of the kind described, comprising a divided card, a plurality of transverse rows of sliver cans in front of such 75 card and a sliver table overlying such cans, in combination with transverse rows of calender rolls on the table respectively adapted to deliver the said divided fleece sections to such cans, the rolls of the first 80 row being spaced to provide passage between them to the rolls of the second row, and means whereby the card drives the said rolls.

4. Apparatus of the kind described, comprising a divided card, a plurality of transverse rows of sliver cans mounted in front 85 of the doffer-comb thereof, each of such cans being adapted for receiving one of the divided fleece-sections, a sliver table overlying 90 such cans and arranged to receive such sections at a substantially uniform distance from the delivery means of the card, and means for moving such sections along the table and into their respective cans. 95

5. Apparatus of the kind described comprising a divided card having a plurality of transverse rows of sliver cans mounted in front thereof and adapted each to receive one of the divided sections of the fleece, and 100 a sliver table overlying the cans and provided with pairs of condensing rolls for moving the fleece-sections along the table and into the cans, in combination with means for driving such rolls including a 105 pinion mounted on and driven by the card and drive shaft connecting said shaft with the said rolls.

6. Apparatus of the kind described, comprising a divided card and a series of rows 110 of sliver cans disposed in front of the same, and a condenser and delivery means adapted to receive each divided fleece section directly from the doffer of the card, in combination with a sliver table overlying the 115 rows of cans and provided with calender rolls for each fleece-section eccentrically mounted with respect to their respective sliver cans, and means for driving such rolls to move the fleece-sections from the said condenser and delivery means, along the table 120 and into their respective cans.

7. Apparatus of the kind described comprising a divided card, a series of rows of sliver cans mounted in front of the same, a 125 trumpet for each fleece-section adjacent the doffer-comb and means for drawing the condensed fleece substantially horizontally therefrom and through the trumpets, in combination with a sliver table overlying 130

- the cans and second trumpets thereon having pairs of calendar rolls for delivering the sections from such trumpets into the cans.
8. Apparatus of the kind described comprising a divided card, a plurality of sliver cans for receiving the sections of the divided fleece, and a sliver table overlying such cans and including pairs of calendar rolls adapted to move such sections along the table toward the cans, in combination with a shaft beneath the table for such rolls and an inclined drive-shaft connecting said shaft with the card for operation thereby.
9. Apparatus of the kind described comprising a substantially flat table, a divided card and means for delivering the sections of its divided fleece upwardly to such table, a pair of calendar rolls mounted in or below an aperture in the table for each fleece, and 20 a rotary sliver can beneath the table and each pair of rolls, and eccentrically disposed with reference to the latter.
10. Apparatus of the kind described comprising a substantially flat table, a divided card having a doffer comb below the table and means at the same level for condensing and delivering the sections of its divided fleece upwardly to such table, in combination with means on the table for advancing such fleece-sections therealong, and a corresponding number of sliver cans beneath the table for receiving such sections.
11. Apparatus of the kind described comprising a divided card having a doffer comb, 35 a sliver table receiving the sections of the divided fleece from such comb, such table being disposed above the doffer and provided with rolls for moving the sections therealong, a corresponding number of sliver cans beneath the table to receive the sections therefrom, and rotary stands for such cans, in combination with a train of gearing on the card, and means for driving said rolls and rotary stands from said train.
- 40 12. Carding apparatus of the kind set forth, comprising a card provided with means for subdividing its fleece into a plurality of sections and having a condensing trumpet and delivery means for each such section, in combination with coiler front apparatus comprising a sliver table adapted to be independently mounted in front of the said delivery means and including a pair of calendar rolls for each section, a series of sliver cans to receive such sections respectively and means for positively driving the said calendar rolls from a revolving part of the card.
- 45 13. A coiler front for divided cards comprising a stand or table having legs adapting it for support on the floor adjacent the front of the card, and adapted to accommodate a group of sliver cans thereunder, in combination with means for conducting divided fleece sections from the card along

the table and through the same to said cans and means for coiling the sections in the cans.

14. Coiler front apparatus for divided cards comprising a separate table adapted 70 for receiving the divided fleece sections and having legs adapted to rest on the floor adjacent the front of the card, a plurality of rotary can stands beneath the table, rolls on the table above the can stands, and means whereby the said stands and rolls are both 75 driven by the card.

15. Coiler front apparatus for divided cards comprising a table structure adapted 80 to receive the divided fleece sections and provided with card-driven rolls for advancing the sections therealong, in combination with a can-stand structure beneath such table structure adapted to support a series of sliver cans beneath said rolls, said structure 85 comprising a series of rotary can stands, a casing, a gear train within the casing and means independent of said rolls for connecting such casing with the card.

16. Apparatus of the kind described, 90 adapted to produce roving capable of direct introduction to the slubber, comprising the combination with a card having means for subdividing its fleece into a plurality of narrow sections, and delivery rolls and trumpets receiving such fleece sections and converting the same into a plurality of slivers or rovings, of a coiler front mounted in front of said rolls and provided with calendar rolls receiving the slivers therefrom, 95 a series of cans disposed beneath said calendar rolls, one for each sliver, and means for coiling said slivers therein.

17. Apparatus of the kind described, 105 adapted to produce roving capable of direct introduction to the slubber, comprising, in combination with a card having a doffer cylinder, a doffer-comb operating substantially at the level of the horizontal radius of said cylinder and means for subdividing its fleece into a plurality of narrow sections, a series of trumpets and delivery rolls receiving the said sections directly from the doffer comb and at substantially the level thereof, coiler front mechanism comprising 110 a series of calendar rolls journaled in front of said trumpets and rolls and above the level thereof, a row of cans having their tops disposed beneath the said rolls and also above said level and each adapted to receive one of said sections, and means for individually rotating the cans.

18. Apparatus of the kind described, comprising the combination of a card having a single doffer cylinder and comb delivering 125 its fleece in a plurality of narrow sections, a trumpet directly receiving each section from the comb, a driven delivery roll journaled in fixed bearings in front of all said trumpets, and a series of aligned shorter rolls rested on 130

and rotated by said driven roll, each said shorter roll nipping the fleece sections directly issuing from two adjacent trunnels against the said driven roll, coiler front 5 mechanism comprising calender rolls, a series of sliver cans beneath said calender rolls, and means for coiling the sliver therein.

In testimony whereof, I have signed this specification in the presence of two wit- 10 nesses.

ELWIN H. ROONEY.
